UNITED STATES PATENT OFFICE

FERDINAND BUCHSTEIN, OF MINNEAPOLIS, MINNESOTA

DEVICE FOR APPLYING PLASTER TO BANDAGES

Application filed June 23, 1930. Serial No. 463,310.

My invention relates to improvements in devices for preparing bandages particularly for use in the formation of casts in orthopedic practices.

In the correction or prevention of deformities in persons, it is often necessary to construct a cast about the body or limb of a patient, the cast to be left in place for the purpose of reinforcing or bracing the deformed or injured member or to be split and removed for the purpose of forming a mold from which a counterpart of the deformed or injured member may be made. In instances such as the latter, the counterparts are often employed as models in the construction of braces and the like for the injured members.

Usually the casts are formed by winding, turn upon turn, about the trunk or other portion of the patient's body a bandage moistened in the roll and which has been impregnated with plaster of Paris. In the process of winding a moistened bandage thus treated with plaster, the turns or layers thereof become rapidly set one upon the other, thus forming a solid shell-like structure.

The bandages are commonly prepared, as occasion requires, by filling or impregnating bandaging material with plaster of Paris as by manually sifting and spreading the plaster upon the material as it is taken from a roll and rewound. This manual process is slow, laborious and extremely unsatisfactory from the standpoint of cleanliness.

A substantial working space is occupied in carrying out the manual process and the plaster is seldom applied to the bandaging material uniformly.

An object of my invention is to provide a simple, durable, compact and inexpensive device by means of which a user may quickly and easily cause the uniform application of plaster to bandaging material in an effective and efficient manner and without the usual disadvantage present in the manual method.

Another object of the invention resides in providing a device in which the bandage is thoroughly and uniformly impregnated with plaster.

Another object of the invention resides in providing a device in which the plaster is

applied to the bandage and the bandage simultaneously formed into a roll.

A still further object resides in providing a support over which the bandage is drawn, and in further providing a sifting drum for sifting the plaster upon the bandage during its travel over said support.

A feature of the invention resides in incorporating in said support a flexible apron, and in providing a spindle on which the bandage is rolled superimposing said apron.

Another object of the invention resides in providing a roller for working the sifted plaster into the bandage.

An object of the invention resides in providing means for urging said apron toward the roller to press the bandage against the same.

Another feature of the invention resides in supporting the apron so that it will bear against the lower portion of the accumulating roll of treated bandaging material.

A still further object resides in mounting the apron to enable it to compensate for the increase in the diameter of the roll of bandage as the same is wound upon the spindle.

A feature of the invention resides in providing a tensioning device for tensioning said apron and thus maintaining the same taut and in contact with the roll of bandage as it winds upon said spindle.

An object of the invention resides in providing the sifting drum with blanking bands for regulating the area over which the plaster is distributed.

Another object resides in forming the support for the bandage with a bed portion and in mounting thereon adjustable guiding means for accommodating bandages of different widths.

Other objects of the invention reside in the novel combination and arrangement of parts and in the details of construction hereinafter illustrated and/or described.

In the drawings:

Fig. 1 is a side elevational view of an embodiment of my invention in devices for applying plaster to bandages.

Fig. 2 is a plan view of the structure shown in Fig. 1, portions thereof being cut away to

100

disclose parts of the construction otherwise concealed.

Fig. 3 is a longitudinal sectional view taken on line 3—3 of Fig. 2.

Fig. 4 is a fragmentary elevational view in detail illustrating the crank for rotating the spindle and the gears for driving the plaster impregnating roller.

Fig. 5 is a fragmentary sectional view taken as on the line 5—5 of Fig. 4 and drawn to a larger scale.

Fig. 6 is a fragmentary cross sectional view of the device taken on the line 6—6 of Fig. 2 and drawn to a larger scale.

Fig. 7 is an enlarged fragmentary sectional view taken longitudinally of the shifting drum.

Fig. 8 is an enlarged fragmentary sectional view of the sifting drum taken as on the line 8—8 of Fig. 2.

Fig. 9 is a sectional view in detail illustrating one of the bandage guides.

The illustrated embodiment of my invention includes a case or frame which I have indicated in its entirety at A and which is in the nature of a box or similar structure open at the top. The case A consists of sides 10 and 11, a bottom 12 and end members 13 and 14. Both of the end members 13 and 14 are spaced from the bottom 12 to leave openings 9 and 19 (Fig. 3) in the case immediately above the bottom 12 thereof. The opening 19 is normally partially obstructed by a closure 16 which is hingedly connected to the end member 14 through hinges 15, said closure 16 being adapted to swing upwardly to enlarge the opening 19 between the end member 14 and the bottom 12 for a purpose presently to be described.

Within the interior of the case A and disposed between the sides 10 and 11 is a supporting structure for a bandage indicated in its entirety by the reference letter B. This supporting structure is disposed generally horizontally and in the operation of the device the bandage material is drawn over the same. Said supporting structure B consists of a bed 17 at one end of the case A and an apron 18 disposed at the other end thereof. The bed 17 is constructed from sheet material of a width equal to the distance between the sides 10 and 11 and is inserted into the case A through the opening 19 thereof below the closure 16. This plate rests upon two rails 20 and 21 attached to the sides 10 and 11 of case A. Said bed 17 protrudes from the case and is formed with a depending lip 22 by means of which it may be readily removed from said case, said lip also serving the additional purpose of guiding a bandage onto the surface of the bed 17. This lip also engages the ends of the rails 20 and 21 and thus provides a stop for limiting the inward movement of bed 17 along said rails.

The apron 18 is constructed of canvas or

other suitable flexible material having a relatively rough surface and is formed at the inner end thereof with a hem 23 through which a rod 24 extends, said rod being attached at its ends to the sides 10 and 11 of the case A immediately below the bed 17. Said apron 18 constitutes a continuation of the bed 17, the outer portion thereof extending freely over and being slidably supported upon a rod 25 extending from wall 10 to wall 11 of the case A across the opening 9. The outer extremity of the apron 18 is formed with a hem 26 in which is disposed a rod 27 which serves as a weight for drawing the apron over the rod 25 and thus tensioning the apron.

At the end of the case A, adjacent the bed 17, is a reel indicated in its entirety at C. This reel includes a shaft 28, the ends 29 and 30 thereof being reduced in diameter to form trunnions which are revolvably supported in two spring arms 31 and 32 attached to the sides 10 and 11 of the case A by screws 33. This shaft 28 may be applied to or removed from the arms 31 and 32 by springing the arm 31 outwardly through the manipulation of a finger piece 34 formed upon the free end of said arm. The reel C also includes a fixed head 35 formed with a hub 135 rigidly secured to the shaft 28 as by means of a pin 136 and further includes an adjustment head 36 which is formed with a boss 37 having a set screw 38 screwed into it and engaging the shaft 28, whereby said head may be adjustably secured to the shaft at any selected position along the same. Said shaft 28 is adapted to receive a roll 39 of gauze or other bandaging material between the heads 35 and 36, the latter being adjusted to accord with the width of the roll.

The bandaging material to be treated is drawn from the roll 39 across the bed 17 and the apron 18, the end of the material being caught upon a spindle 41 best shown in Figs. 2 and 3. This spindle is preferably constructed rectangular in cross section and is supported as follows: Upon the exterior of the side 11 of the case A is a plate or bar 45 which is attached to said case by screws 137. Secured to this bar 45 is a bearing 44 formed with a socket 43 adapted to receive the reduced rounded end 42 of the spindle 41. The opposite end 46 of the spindle 41 is also turned down, the extremity thereof being formed with an open slot 54. A second plate 47, mounted on the side 10 of the case A, is secured thereto by screws 138. Secured to this plate is a bearing 48 having a bore 49 extending therethrough. This bore 49 revolvably receives the inner end of a removable sleeve 50, the bore 139 of said sleeve, in turn, receiving the shank 109 of a crank 51 having a handle 52, said shank being secured to the sleeve 50 by means of a pin 140. The inner end of the sleeve 50 receives the reduced end 46 of

spindle 41 and is fitted with a pin 53 which engages in the slot 54 in the spindle end 46 and forms a coupling between said sleeve and spindle. It is to be noted that the diameter of the bore 49 in bearing 48 is greater than the largest diametrical dimension of the spindle 41 so that when the sleeve 50 is removed the angular portion of the spindle may enter said bore 49 sufficiently to permit of the removal of the end 42 thereof from the bearing 44 on the opposite side of the case. In this manner, when a bandage has been wound on the spindle 41, spindle and bandage together may be removed from the case and the completed bandage roll thereafter removed from the spindle.

The device will accommodate bandages of various widths. For guiding the bandaging material along the bed 17, I provide on said bed two guides 55 and 56. The guide 55 is rigidly secured to the bed 17, while the guide 56 is adjustable transversely thereof. Said guide 56, shown in detail in Fig. 9, consists of a strip of sheet metal which is bent U-shaped to provide a flange 57 adapted to underlie the bandage material and a flange 58 adapted to overlie the same. The flange 58 is constructed with a notch 59 cut back substantially to the portion 60 of the guide which connects the two flanges 57 and 58. Attached to the flange 57 opposite the notch 59 is a pin 61 formed with a reduced end 142 which extends into an opening 141 and is riveted to said flange. The pin 61 passes through a slot 62 in the bed 17, said slot extending transversely across the bed. Encircling the pin 62 beneath the bed 17 is a compression coil spring 65 which is seated between two washers 66 and 67 on said pin. The washer 66 bears against the underside of the bed 17, while the washer 67 bears against a cotter key 68 passing through the lower end of the pin 62. By means of this construction, the guide 56 is frictionally held in position upon the bed 17 and may be slid from one end of the slot 62 to the other so as to accommodate any desired width of material. For the purpose of preventing rotation of the guide 56, the pin 61 is flattened on opposite sides as indicated at 143, which portions of said pin fit snugly within the slot 62. The guide 55 may be attached to the bed 17 in the same manner as the guide 56 or it may be riveted to the bed 17, as desired.

To maintain the fabric in contact with the face of the bed 17, a finger 72 is employed, the same being connected to the bed 17 near one edge thereof by means of a hinge 73. This finger may be swung upwardly to permit of the insertion of the bandage material between it and the bed and when said finger is released it acts through gravity to hold the material in contact with the bed.

For the purpose of depositing plaster upon the bandaging material, a hollow cylinder or

drum 74 is employed. This drum includes two heads 75 and 76 having flanged hubs 77 secured to a shaft 78. This shaft is journaled in two bearings 86 and 87 secured to the sides 10 and 11 of the case A by means of screws 88. At their peripheries, the drum heads 75 and 76 are shaped to provide annular reinforcing beads 149 (Fig. 7) and also inwardly extending rim portions 79. Spanning the space between the rim portions 79 of the drum heads 75 and 76 are two spaced bars 85, the same being secured at their ends to said rim portions and forming between them an opening 81. Closing this opening is an arcuate door or closure 82 consisting of a frame 83, supplied with a covering 84 of screen wire or the like, one side bar of said frame 83 being secured to one of the bars 85 by means of hinges 145. Supplementing the closure 83 and completing the peripheral portion of the drum body is a covering 80 of screen wire or the like, the same being secured along its sides to the rim portions 79 of the drum heads 75 and 76 and along its ends to the bars 85. A latch bar 146 is employed for releasably securing the door 82 closed. This latch bar has hooks 147 and 148 formed at the opposite ends thereof, the same being adapted to hook over the beads 149 of the head plates 75 and 76 of the drum 74. The latch bar 146 is somewhat resilient and may be sprung to disengage the hook 148 from the bead 149 with which it cooperates, by manipulating a finger piece 150 formed at the end of said hook. A keeper 151 attached to the head plate 76 indicates to the user the proper position for application of the latch bar to the drum and assists in preventing the latch bar from moving peripherally on the drum. In the use of the device, the drum 74 is rotated upon the revolution of the shaft 78, which causes the plaster, placed within the drum through opening 81, to be sifted through the coverings 80 and 82 and deposited upon the bandage supported by the bed 17 and apron 18.

The plaster, deposited upon the bandage is worked into the mesh and material thereof by the roller 89 as the bandage is drawn across the apron 18. This roller 89 is rigidly mounted on a shaft 90 journaled in the two plates 45 and 47 on sides 10 and 11 of case A, the lowermost portion of the roller being disposed below the level of the bed 17.

In conjunction with the apron 18, a presser 120 is employed which is indicated in its entirety at 91. This presser comprises a frame consisting of two bars 92 disposed longitudinally of the case A (Figs. 2 and 3) and two cross bars 93 and 94. The bars 93 and 94 have downwardly bent ears 95 at the ends thereof which are fastened to the ends of the bars 92 by rivets 96. A shaft 97 extending through the bars 92 and the sides 10 and 11 of case A pivotally supports the frame of the presser 130

91 beneath the apron 18. Attached to the frame bars 93 and 94 of the presser 91 is a flexible back 98 constructed of leather or other suitable material. The ends of this back are secured to the bars 93 and 94 and the intermediate portion thereof rides upon a rod 99 traversing the case A and secured at its ends to the sides 10 and 11 of said case. This rod 99 is disposed immediately beneath the bed 17 and forms a support for the back 98 which in turn supports the apron 18 along the inner end of the bed 17. A tension coil spring 100 is stretched between the frame member 94 of the presser 91 and an eye 101 secured to the bottom 12 of the case A. This spring tilts the presser frame and acts through the back 98 and apron 18 to yieldingly press the bandage against the lower portion of the roller 89. The parts are so arranged that the end 102 of the presser 91 extends above the lowermost portion of roller 89 so as to form an undulation in the apron 18 by reason of which the bandage is kept in close contact with said apron 18.

25 The roller 89 is driven from the sleeve 50 which turns the spindle 49, through a transmission device illustrated in detail in Figs. 4 and 5. Attached to the plate 47 midway between the centers of the shaft 90 and the sleeve 50 is a stud 103, said stud being formed with a reduced portion 144 which is received in a counter-sunk hole 145 in said plate and riveted to the plate. Upon this stud is rotatably mounted an idler pinion 104 which 30 meshes with a gear 105 fast to the sleeve 50 and a similar gear 106 fast to the shaft 90. The gear 105 is secured to the sleeve 50 by means of the pin 140 which projects into the hub 108 of said gear and which, as previously explained, passes through the sleeve 50 and the shank 109 of crank 51 in the outer end of said sleeve. The gear 106 is secured to the shaft 90 by means of a pin 110 extending through the hub 111 of said gear and 35 through said shaft 90. The gear 104 is free to rotate upon the stud 103 but is held from axial movement thereon by a washer 112 backed by a cotter key 113 passing through said stud. By means of this construction 40 the roller 89 is rotated in the same direction as the spindle 41 so that said roller assists in drawing the bandage along the apron 18 as the crank 51 is rotated.

45 A gear guard 114 is employed to cover the teeth of the gears 104, 105, and 106. This guard is constructed of sheet metal bent as best shown in Fig. 4 and formed with ears 115. Screws 116 passing through these ears and into the side 10 of case A secure the guard 50 114 in place.

The sifting drum 74 is driven from the shaft 90. A sheave 117, mounted upon one end of the shaft 90 at one side of case A is secured to said shaft by means of a pin 118. 55 Likewise, a sheave 119, mounted upon the

corresponding end of the shaft 78 is secured thereto by a pin 120. These sheaves 117 and 119 are disposed in the same plane, a crossed round belt 121 passing about the same to drive the sifting drum 74 in a direction opposite to the direction of rotation of the roller 89. When the crank 51 is turned all of the moving parts of the device are simultaneously operated.

In use, a roll of bandaging material is applied to the reel C, said reel being first freed from the arms 31 and 32 by grasping the finger piece 34 on arm 31 and springing the same outwardly. The set screw 38 is loosened and the head 36 slipped from the shaft 28. The roll of material to be used is then placed upon the shaft 28 and the head 36 replaced and the set screw 38 tightened to hold it in proper position. The reel C is next remounted in the arms 31 and 32. As previously indicated, the machine is capable of handling any width of material which can be accommodated between the fixed guide 55 and the adjustable guide 56. For the purpose of illustration, I have shown in the drawing a roll 39 of material of a width considerably less than the maximum width of material for which the device is designed.

After the roll of material has been properly applied to the reel C, the door 16 is raised to give access to the interior of the case A. The end of the roll is then threaded through the opening 19 uncovered by the door and thence through the guide 55 on bed 17. The finger 72 is then raised, the material being drawn beneath it and thence fed under the roll 89 which is caused to be rotated by turning crank 51 to draw the material along the apron 18. The end of the bandage material is then turned about the square spindle 41. Due to the shape of this spindle the material is satisfactorily caught thereon without the use of special attaching means. With the roll 122 started upon the spindle 41, the run 123 of the bandage is drawn along the upper surface of the bed 17 and the apron 18 as the crank 51 is turned. After the bandage has been attached to the spindle 41, the adjustable guide 56 is brought into proper position, as clearly shown in Fig. 2. The door 16 is then closed and the run 123 of the bandage material is ready to receive the plaster of Paris.

For the purpose of controlling the lateral extent of the plaster discharged from the drum 71, I employ blanking bands of different widths, one thereof being shown at 124. The selected band is inserted in the drum 74 at the end thereof opposite the side of the machine on which the run 123 of the bandage is disposed. This band 124 is of such width that the plaster when sifted from said drum will fall only upon the run 123 of the bandage, said band being constructed of sheet material, preferably of a resilient

nature, and formed so that its ends 125 and 126 overlap. In some instances several bands may be used in conjunction with one another and arranged in proper axial relation to give the desired blanking effect.

A suitable quantity of plaster is introduced into the interior of the drum 74 through the opening 81 therein and the closure 82 is swung shut and latched in place by the latch member 146. The machine is then operated by turning the crank 51 in a counter-clockwise direction as viewed in Fig. 4. Thus, the roller 89 and drum 74 are rotated and the bandage is wound upon the spindle 41 from the bottom thereof. As the operation proceeds, the plaster within the drum 74 is sifted through the covering of screen and is deposited upon the run 123 of the bandage. As the bandage passes between the apron 18 and the roll 89, the plaster is pressed into the meshes of the bandage material. Due to the 15 construction of the apron 18 of canvas, it has a sufficiently rough surface so that the plaster is prevented from sliding freely along the same. This causes the material to travel through the layer of plaster on the apron and further assists in rubbing and working the plaster into the bandage. Due to the 20 construction and action of the presser 91, the run 123 of the bandage is maintained in intimate contact with the apron 18.

Due to its particular mounting, the apron 18 is self-conformable to the roll of the completed bandage as it accumulates upon the 25 spindle 41. Thus, the apron, at that portion thereof beneath the roll, performs the final rubbing or pressing of the plaster into the material. It further tends to keep the plaster from becoming dislodged from the material 30 in the roll and serves to reapply it should it become dislodged. In this manner, a maximum amount of plaster is imbedded in the bandage, whereby it may be expected to function in the most efficient manner. As the roll 35 122 increases in diameter (dotted lines at 127 in Fig. 3), the free end of the apron 18 is drawn back over the rod 25 to occupy the position such as shown in dotted lines at 128 in Fig. 3. The weight 27 maintains the 40 apron 18 taut so that it is always in the proper position to function and produce the desired results.

After the roll 122 is completed, the sleeve 50 is withdrawn from the bearing 48, thus disengaging the pin 53 from the open ended slot 54 in the spindle 41. Then, by sliding the spindle 41 into the bore 49 of the bearing 48, the end 42 of said spindle becomes disengaged from the opposite bearing 44. The 55 spindle 41 may thereafter be bodily removed from the device and the roll 122, in turn, removed from the spindle. Thereafter, the spindle may be reapplied to the machine for future use.

In order that the interior of the device may

be kept clean and to permit of the removal of any plaster which may sift down upon the bottom 12, the rods 24 and 99 and the shaft 97 are all removable so that the apron 18 and the presser 91 may be detached and removed from the case A. And the bed 17 is slidably mounted on the rails 20 and 21 so that it may be removed from the end of the case through the opening 19. In this manner, the removable parts may be readily cleaned, inspected and repaired, as the occasion demands, and the interior of the case A also may be readily cleaned.

My invention is highly advantageous in that a simple and efficient device is provided, whereby plaster may be readily and effectively applied to bandages. The application of the plaster to the bandage is accomplished automatically. The device operates economically avoiding in large degree the waste of material. The device is so encased as to retain the plaster within the same, thereby keeping the surrounding working space free from unsightly accumulations. The device is adjustable to accommodate bandages of 80 different widths. All of the parts are easily accessible and a number thereof readily removable for inspection or repair or for the purpose of facilitating the cleansing of parts. The device can be constructed at a nominal 85 cost and will not readily get out of order.

Changes in the specific form of my invention as herein described may be made within the scope of what is claimed without departing from the spirit of the invention.

Having described my invention what I claim as new and desire to protect by Letters Patent is:

1. A device for applying plaster to bandages comprising a substantially horizontal supporting apron, means for drawing a bandage over said apron, means superimposing said apron for depositing plaster upon the bandage supported thereby, a roller contacting with the plaster treated surface of said bandage and adapted to press the plaster into said bandage, a pivoted frame for said apron, and means for yieldingly tilting said frame to press the bandage against the roller through the intermediary of said apron.

2. A device for applying plaster to bandages comprising an apron disposed substantially horizontally, means for drawing a bandage over said apron, means superimposing said apron for depositing plaster upon the bandage supported thereby, a roller contacting with the treated surface of said bandage for working the plaster into the same, a movable frame for said apron, and means for moving said frame to elevate the apron, and through it, press the bandage against said roller.

3. A device for applying plaster to bandages comprising a support, means for drawing a bandage over said support, a sifting

70

125

130

drum superimposing said support and having a perforate wall for sifting plaster upon said bandage, and a blanking band disposed within said drum and adapted to lap a portion of said wall for limiting the area of the surface over which the plaster is sifted.

4. A device for applying plaster to bandages comprising a support forming a substantially horizontal supporting surface, a reel disposed near one end of said surface for carrying the supply of bandage to be treated, a spindle superimposing and disposed near the other end of said surface for drawing the bandage over said surface and winding it in a roll, means for depositing plaster upon the bandage during its travel over said surface, said surface contacting with said bandage, a portion thereof being movable to conform with the increasing diameter of the roll of bandage accumulating upon said spindle.

5. A device for applying plaster to bandages comprising an apron, means for drawing a bandage along said apron and in contact therewith, said means including a spindle disposed above the apron and adapted to wind the bandage thereon, means for depositing plaster upon the bandage in its travel along the apron, said apron being yieldable to the roll of bandage accumulating on said spindle.

6. A device for applying plaster to bandages comprising a frame, an apron attached at one end to said frame, a spindle mounted in said frame and superimposing said apron, said spindle being adapted to draw a bandage across said apron and wind the same up in a roll thereon, means for depositing plaster upon the bandage, a roller mounted in said frame engaging said bandage for working the plaster into the bandage, supporting means for said apron disposed therebeneath and between said roller and spindle, and other supporting means for said apron, the same being disposed at the side of said spindle opposite said roller and above the lowermost portion of the spindle, said last mentioned means being adapted to slidably support said apron, and means for tensioning the apron over said last supporting means, said apron being adapted to conform itself to the lower portion of the roll accumulating on said spindle.

7. A device for applying plaster to bandages comprising a frame, a yieldingly tensioned apron therein, a spindle detachably mounted in said frame and superimposing said apron, said spindle being adapted to draw a bandage along said apron in contact therewith and to wind the bandage in a roll thereon, means for depositing plaster upon the bandage, means for working the plaster into the bandage, and supporting means for the apron disposed at either side of said spindle and at elevations approximating that of said spindle.

8. A device for applying plaster to bandages comprising a frame, a yieldingly tensioned apron therein, a spindle mounted in the frame and superimposing said apron, said spindle being adapted to draw a bandage along said apron in contact therewith and to wind the bandage in a roll thereon, means for sifting plaster into the meshes of the traveling bandage, and supporting means for said apron disposed at either side of the spindle and at elevations approximating that of said spindle, said apron being self-conformable to the lower portion of the roll of bandage accumulating on the spindle and forming a pocketing means for catching the plaster dislodged from the roll and for re-applying the dislodged plaster to the roll.

9. A device for applying plaster to bandages comprising a frame, a yieldingly tensioned apron therein, means for drawing a bandage over the apron, means for depositing plaster upon the moving bandage, a device for engaging the plaster covered surface of the bandage to work the plaster into the bandage, and means for mounting the apron in said frame, said means cooperating with said device to form an undulation in the apron dipping beneath said device.

10. A device for applying plaster to bandages comprising a frame, a spindle upon which a bandage is adapted to be wound in a roll, means for depositing plaster upon the bandage prior to its entry to the roll, a device in advance of the spindle for working the plaster into the bandage, a support for the bandage consisting of a tensioned yielding apron, and means for mounting said apron to provide undulations therein occupied in one trough by said device and in another thereof by the roll accumulating on said spindle.

11. A device for applying plaster to bandages comprising a frame, a spindle mounted in the frame and adapted to wind a bandage in a roll thereon, means for depositing plaster upon the bandage prior to its entry to the roll, and an apron superimposed by the spindle and yieldingly tensioned against the accumulating roll thereon in conformity with the lower portion of said roll.

In testimony whereof I affix my signature.

FERDINAND BUCHSTEIN.
